UNITED STATES PATENT OFFICE

THORVALD PETERSEN, OF ERIE, PENNSYLVANIA, ASSIGNOR TO REED MANUFACTURING COMPANY, OF ERIE, PENNSYLVANIA, A CORPORATION OF PENNSYLVANIA

DIESTOCK

Application filed August 6, 1924. Serial No. 730,438.

This invention relates to die stocks and is designed to improve the simplicity and efficiency of the structure. It involves a head with a ratchet handle ring mounted thereon and a telescopic handle with means for frictionally holding the telescoping members in adjustment. It also involves an adjustment for the chasers which comprises handles by which the die may be backed off the threads. It also involves an improvement in the adjustable follower preventing the clogging of the adjustable devices with chips.

The invention is illustrated in the accompanying drawings as follows:—

Fig. 1 shows a side elevation, partly in section, on the line 1—1 in Fig. 2.

Fig. 2 a plan view of the structure.

1 marks the head. It has a bearing surface 2 on which a handle ring 3 is mounted. The bearing surface 2 is provided with ratchet teeth 4 and a ratchet pawl 5 operates on these teeth. The ratchet pawl is mounted in an opening 6 in the head and has an extension 7 which passes through a collar 8 screwed into the socket. A spring 9 is arranged between the collar 8 and the pawl 5 and yieldingly holds the pawl in engagement with the teeth. A handle 10 is arranged at the outer end of the extension by means of which the pawl may be reversed so that the ratchet may be reversed in direction. Two of these ratchet pawls are provided. By means of them they may be locked against ratchet movement in either direction or the ratchets may operate in either direction.

A handle socket 11 extends from the ring 3 and a fixed portion of the handle 12 is screwed into the socket 11. A telescopic or sliding member 13 slides in the fixed member 12. It is desirable to have a yielding adjustment for the sliding member and this is simply accomplished in the present mechanism by a spring loop 14, the ends of which extend through a plate 15 locked in the socket 11 when the fixed member 12 is screwed to place. This loop is initially larger than the opening in the sliding member and thus frictionally engages its walls and yieldingly locks the handle in adjustment in different positions. A stop pin 16 extends through the loop and

locks the telescopic member in the fixed member.

Chasers 17 have openings 18 through which screws 19 extend for securing the chasers on the head. Adjusting screws 20 are provided back of the chasers and these screws extend through backing-off handles 21. The screws have the wrench-holds 20^a and these wrench-holds extend into sockets 22 in the ends of the backing-off handles 21. The backing-off handles are of particular use in connection with the ratchet driven head in that the die may be spun off the work by these backing-off handles without swinging the long telescopic handle.

The adjustable follower comprises the following blocks 23. These extend radially from openings 24 in the head and the blocks slide in guides 25 in the head. The blocks have projections 26 which extend into scroll grooves 27 in a scroll plate 28. The scroll plate is journaled on the head and secured thereon by a nut 29.

By making the projection on the blocks but a single projection is necessary and the opening 24 can be made to closely fit the follower block so that no chips can enter into the scroll grooves or the guides for the block. Thus the adjustment is always readily workable and never clogged by chips from the work.

What I claim as new is:—

1. In a die stock, the combination of a head; a telescopic handle on the head comprising a fixed member on the head and a sliding member; a spring loop secured to one of the members and frictionally engaging the interior of the other member; and a stop extending into the loop limiting the telescopic movement.

2. In a die stock, the combination of a head having a handle socket thereon; a fixed member of the handle secured in the socket; a hollow sliding member sliding in the fixed member; and a spring loop secured to a plate, the plate being secured in the socket by the fixed member, said loop yieldingly engaging the walls of the telescopic member.

3. In a die stock, the combination of a head having a handle socket thereon; a fixed

member of the handle screwed into the socket; a hollow sliding member sliding in the fixed member; a spring loop secured to a plate, the plate being secured in the socket by the fixed member, said loop yieldingly engaging the walls of the telescopic member; and a stop pin in the sliding handle extending through the loop.

4. In a die stock, the combination of a head; a telescopic handle on the head comprising an outer member fixed on the head and a hollow inner member telescopically arranged within the fixed member; and a U-shaped spring loop having the ends of the U secured to the fixed member and having the closed end of the U extending into the inner member, the sides of the loop frictionally engaging the inner walls of the inner member and yieldingly holding the inner member in adjustment in the fixed member.

20 In testimony whereof I have hereunto set my hand.

THORVALD PETERSEN.
